UNITED STATES PATENT OFFICE.

WILLIAM A. BASHAW, OF WILKINSONVILLE, MASSACHUSETTS.

SHUTTLE BLOCK.

Application filed October 25, 1924. Serial No. 745,904.

To all whom it may concern:

Be it known that I, WILLIAM A. BASHAW, a citizen of the United States, residing at Wilkinsonville, in the county of Worcester 5 and State of Massachusetts, have invented a new and useful Shuttle Block, of which the following is a specification.

This invention relates to a self-threading shuttle block particularly designed for use in automatic weft replenishing looms. It is essential that such shuttle blocks should be very easily threaded by simply drawing the thread over the shuttle block. It is also essential that such shuttle blocks shall remain 15 threaded under all conditions of operation. It sometimes happens that a loop will be formed in the weft or filling as it is drawn from the bobbin and such a loop frequently causes unthreading of the shuttle block.

20 It is the object of my invention to improve the construction of such shuttle blocks to the end that accidental unthreading thereof may be substantially eliminated.

In the preferred form of my invention I 25 have provided an inner sleeve in the thread passage, having a forwardly projecting portion adapted to engage the thread and prevent unthreading of the shuttle block.

The preferred form of the invention is 30 shown in the drawings in which

Fig. 1 is a partial plan view of a shuttle having my improved shuttle block mounted therein;

Fig. 2 is a transverse sectional end elevation, taken along the line 2—2 in Fig. 1;

Fig. 3 is a side elevation, partly in section, of my improved shuttle block;

Fig. 4 is a side elevation of the inner sleeve for the thread passage;

Fig. 5 is an end view thereof, looking in the direction of the arrow 5 in Fig. 4, and

Fig. 6 is a perspective view thereof.

Referring to the drawings, I have shown a portion of a shuttle 10 in which my improved shuttle block 11 is inserted and secured in any usual manner. In its general features the shuttle block may be greatly varied in construction and the particular shuttle block shown in the drawings is illustrative only, except as to features herein-after particularly pointed out.

The shuttle block 11 has a thread passage 12 of substantially circular outline and provided with a longitudinal slot or opening 13 55 in its upper portion for the entrance of the thread when the shuttle is being threaded.

The axis of the thread passage 12 is substantially aligned with the bobbin or weft carrier B. The shuttle is provided with the usual opening or outlet 14 at the side from 60 which the weft W extends to the fabric. My invention consists primarily in providing means for preventing rearward unthreading movement of the weft W through the thread passage 12.

In the preferred form of my invention I accomplish this purpose by inserting an inner sleeve 15 in the thread passage 12, the sleeve being preferably a drive fit in the thread passage and being held by friction 65 therein. The sleeve 15 is provided with a longitudinal slot or opening 16 which is preferably positioned at one side and below the center line of the sleeve when the latter is in operative position, as indicated in 75 Fig. 12.

In its upper part, a portion of the sleeve 12 is cut away so that its outer convex surface is of less radius than the sleeve 15. A notch or recess 18 is also formed at the front 80 end of the sleeve 15 and the rear corner of the portion 17 is cut away or bevelled as indicated at 20.

When the sleeve 15 is in position in the thread passage 12 of the shuttle block 11, the weft thread may be readily inserted therein, the thread passing down through the slot or opening 13 and then sliding downward and sideways over the projecting portion 17 of the sleeve until it enters the slot 90 16 thereof, through which it passes to the central thread passage of the sleeve. The sleeve 15 thus forms no obstruction to the easy threading of the shuttle block.

If the thread loops backward, it must 95 move backward along the slot or opening 13 and while thus positioned it is guided into the notch or recess 18 of the sleeve 15 and is thus effectively prevented from throwing out of the slot 16. The bevelled rear corner 100 20 of the projection 17 permits easier threading of the shuttle block.

While I have shown my invention as embodied in a shuttle block of the particular type, it will be understood that my invention 105 may be used with any shuttle block having a thread passage with an upper slot or opening 13 or any similar or equivalent construction.

While the sleeve 15 forms a very small 110 and inconspicuous addition to a shuttle block, it has been found to very greatly re-

duce the occurrence of mis-threading or un-threading during the operation of the shuttle.

5 The sleeve may also be formed integral with the shuttle block by a process of die-casting or otherwise, as will be evident to those skilled in the art.

10 Having thus described my invention and the advantages thereof, I do not wish to be limited to the details herein disclosed otherwise than as set forth in the claims, but what I do claim is:—

15 1. In a loom, in combination, a shuttle having a shuttle block with a thread passage having a longitudinally extended thread admitting opening therein and a sleeve in said passage through which said thread extends freely axially from end to end thereof when in running position, said sleeve having 20 a slot offset angularly from said thread opening and said sleeve having a reentrant recess at the forward end thereof adjacent the longitudinal opening in said thread pas-

sage and said sleeve having a forwardly projecting loop-catching portion between said recess and said slot.

2. In a loom, in combination, a shuttle having a shuttle block with a thread passage having a longitudinally extended thread admitting opening at one side thereof and 30 a sleeve in said passage slotted longitudinally and having a portion reduced in outside diameter to admit a thread from said entrance opening, said sleeve being positioned with its slot substantially out of alignment 35 with said entrance opening and said sleeve having a reentrant recess at the front end thereof adjacent said entrance opening but separated from said slot, said recess being effective to receive and hold a backward 40 looping thread and to thereby prevent un-threading of said shuttle block.

In testimony whereof I have hereunto affixed my signature.

WILLIAM A. BASHAW.
